C. W. BROWN

SIGNAL

Filed Feb. 1, 1922

FIG. 1.

FIG. 2.

FIG. 3.

Inventor:
Charles W. Brown
by Herbert W. Jenner
Attorney.

UNITED STATES PATENT OFFICE.

CHARLES W. BROWN, OF CLEVELAND, OHIO.

SIGNAL.

Application filed February 1, 1922. Serial No. 533,272.

To all whom it may concern:

Be it known that I, CHARLES W. BROWN, a citizen of the United States, residing at Cleveland, in the county of Cuyahoga and 5 State of Ohio, have invented certain new and useful Improvements in Signals, of which the following is a specification.

This invention relates to signals adapted for use on motor cars to indicate, at night as 10 well as in the day, the direction in which the car is about to turn, and which may also be used to indicate that the car is about to stop or to start.

This invention consists in the novel construction and combination of the parts hereinafter fully described and claimed whereby 15 two electric glow lamps are supported and are operated by hand to effect the required signals.

20 In the drawings, Figure 1 is a front view of a signal constructed according to this invention. Fig. 2 is a sectional plan view, taken on the line 2—2 in Fig. 1. Fig. 3 is a cross-section, taken on the line 3—3 in 25 Fig. 2.

A casing 6 is provided, and is secured to the motor car at any suitable point. The front 7 of the casing has two horizontal arrows 8 and 9, arranged one above the other 30 and pointing in opposite directions. The front may also have other indicators, such as the words "Left" and "Right," or may have both arrows and words. The interior 35 of the box is coated with white enamel 4 to reflect the light, and the arrows are preferably formed of red glass 5 covering arrow-shaped openings in the front 7. The casing is provided with horizontal guides 10 at its middle part between the arrows, and 40 its front 7 is removable. The back of the casing may also have arrows the same as its front.

A plate 12 of insulating material is provided, and is slidable horizontally on the 45 guides 10 which are preferably formed of metal together with the casing, and are grounded by any approved means. The plate 12 has two holes 14, and 15 and 16 are two electric lamps of approved construction 50 supported by the plate 12. The lamp sockets are slid into the holes 14, and one lamp is arranged to project upwardly and the other downwardly so that the light from

them may shine through the respective arrows. Radial holes 17 are formed in the 55 plate 12 between the holes 14 and the ends of the plate, and helical springs 18 are arranged in these holes between the lamp sockets and the metal guides. These springs 60 secure the lamps in position in the plate 12, and place the lamp sockets in circuit with the ground.

The lamps have end contacts 19 in the usual way, and 20 are contact springs which bear on the contacts 19, and are secured to 65 the plate 12 by bolts 21. Line wires 24 and 25 are secured to the bolts 21, and project through a short tube 26 let into the bottom of the casing. The wires are provided with a suitable electric battery 27 and switches 70 28; so that a current of electricity may be sent through either lamp, or through both of them simultaneously.

The lamps can be renewed with great facility by sliding the plate 12 out of the casing after the front is opened. A sounder or annunciator of any approved construction may also be advantageously included in circuit with each lamp, to draw attention to the signal illuminated by it. The direction 75 of each arrow corresponds with the direction the car is about to take in turning, and when both arrows are illuminated it indicates that the car is either about to stop or to start.

80 What I claim is:

1. In a signal, a casing provided with a front having direction indicators arranged one above another, said casing having also horizontal guides at its sides between the 90 indicators, a plate of insulating material slidable on the said guides and provided with lamp holes, electric lamps having their sockets inserted in the said holes, means for grounding each lamp independently of the other, said lamps being arranged to project one above and the other below the said plate, and means for completing an electric circuit through each lamp to illuminate the indicator to which it pertains.

95 2. In a signal, a metallic casing provided with a front having direction indicators arranged one above another, said casing having also horizontal metallic guides at its sides between the indicators, a plate of insulating material having its ends slidable 100

105

on the said guides, said plate having lamp holes in its middle portion and radial holes extending horizontally between its lamp holes and its ends, electric lamps having their sockets inserted in the lamp holes, helical contact springs arranged in the radial holes between the lamp sockets and the said

guides, and means for completing an electric circuit through each lamp to illuminate the indicator to which it pertains. 10

In testimony whereof I have affixed my signature.

CHARLES W. BROWN.
